UNITED STATES PATENT OFFICE

127,709

DESIGN FOR A COMBINED BURNER, BOWL, AND UTENSIL SUPPORT FOR STOVES

William T. Bradbury, Millersport, and Herman F.
Lieber, Newark, Ohio, assignors to Newark Stove
Company, Newark, Ohio, a corporation of Ohio

Application March 31, 1941, Serial No. 180,041

Term of patent 7 years

To all whom it may concern:

Be it known that we, William T. Bradbury and Herman F. Lieber, citizens of the United States of America and residents of Millersport, in the county of Fairfield and State of Ohio, and Newark, in the county of Licking and State of Ohio, respectively, have invented a new, original, and ornamental Design for a Combined Burner, Bowl, and Utensil Support for Stoves, of which the following is a specification, reference being had to the accompanying drawing, forming a part thereof.

Fig. 1 of the drawing is a plan view of a combined burner, bowl and utensil support for stoves embodying our new design.

Fig. 2 is a perspective view of the same.

Fig. 3 is an elevational view partly in section taken on line 3—3 in Fig. 1.

We claim:

The ornamental design for a combined burner, bowl, and utensil support for stoves, substantially as shown.

WM. T. BRADBURY.
HERMAN F. LIEBER.
